UNITED STATES PATENT OFFICE.

WILLIAM WATERMAN MCCALLIP, OF COLUMBUS, OHIO.

MUSICAL INSTRUMENT.

SPECIFICATION forming part of Letters Patent No. 644,022, dated February 20, 1900.

Application filed August 28, 1899. Serial No. 728,706. (No model.)

To all whom it may concern:

Be it known that I, WILLIAM WATERMAN MCCALLIP, a citizen of the United States, residing at Columbus, in the county of Franklin and State of Ohio, have invented certain new and useful Improvements in Musical Instruments; and I do hereby declare the following to be a full, clear, and exact description of the invention, such as will enable others skilled in the art to which it appertains to make and use the same.

The invention relates more particularly to instruments that include in combination a cithern or either - like instrument and a mouth-harp or harmonica, and the features of novelty are set forth in the claims appended to the following description.

In the accompanying drawings, showing one embodiment of my improvements, Figure 1 is a view of the right-hand side of the instrument. Fig. 2 is a view of the left-hand side of the instrument, the mouth-harp attachment being removed. Fig. 3 is a front view of the upper portion of the instrument. Fig. 4 is a top view. Fig. 5 is a vertical sectional view, on a larger scale, through the mouth-harp and its sound-chamber.

Like characters of reference in the several views designate corresponding parts.

30 1 designates the body of the stringed instrument, which is of the general form of a cithern, but is furnished on each of its larger flat sides with bridges and pins, as shown, to which strings can be attached in the usual manner, one set of the pins on each side being rotatable to permit the tuning of the strings. The strings on the right-hand side are shown to be sixteen in number, so that they may be tuned to form a diatonic scale of 40 two octaves, while those on the left side are twelve in number, so that they may be tuned to form three common chords—as, for example, chords of the tonic, dominant, and sub-dominant, with their bases or fundamentals. 45 The strings are thus arranged to suit the normal difference between the dexterity of the right and left hand, it being more difficult to pick a melody than to pick chords.

2 designates the sound chamber or chest of 50 the mouth-harp. This chest may be of the form shown—that is, with a substantially-rectangular portion or pocket adapted to receive

a mouth-harp and a tapering portion, in the end of which is formed or fitted a screw. The upper side of the sound-chamber has a sliding cover 2^a, so that the chamber may be opened more or less to vary the volume and quality of the tone emitted. The mouth-harp is held in its seat in the end of the sound-chamber by means of a plate 3, having holes 55 that correspond to and register with the air-passages of the mouth - harp. Where the sound-chamber is of wood, this plate may be secured in place by means of nuts or small bolts passing through small holes in the ends 60 of the plate and in small brackets fastened to ends of the sides of the sound-chamber.

The longitudinal edges of the perforated plate 3 project beyond the sides of the sound-chamber, and upon these edges fit flanges of 70 a mouthpiece 4. This mouthpiece is made with a hole, through which breath is blown or drawn to vibrate the reeds of the mouth-harp, and the mouthpiece is capable of being slid back and forth across the plate 3 to 75 bring the hole of the mouthpiece over any of the various air-passages of the mouth-harp. The inner side of the mouthpiece may be furnished with a padding of felt to prevent the escape of air at the sides. The screw on the 80 end of the sound-chamber is designed to enter and frictionally engage a threaded socket 1^a in the front edge of the cithern, so that, if desired, the sound-chamber, together with its contained mouth-organ, may be turned to 85 stand in an inclined position with respect to the strung side of the cithern and enable the player to see the strings.

At any suitable place on the top of the cithern I place chart-holder 5, and by means of 90 a pointer 4^a, secured to the mouthpiece, and a suitable notation on a chart in the holder the mouthpiece may be guided to the proper position to play a melody. The rear side of the cithern will preferably have a loop or strap 95 handle, into which the fingers of the left hand may be placed to hold the instrument, so that the thumb of the left hand shall be free to pick chords on the left side and the right hand be free to pick a melody on the 100 right side.

As may readily be inferred, a variety of kinds of music may be produced with this instrument, to wit, a melody alone picked on

the strings—a melody with chord accompaniment on the strings, a melody on the mouth-harp with an accompaniment of chords on the strings, and a melody and chord accompaniment on the strings with an alto or tenor on the harp.

What I claim, and desire to secure by Letters Patent, is—

1. A stringed instrument of the cithern kind, combined with a holder having a seat for a harmonica or mouth-harp, with means for rotatably attaching the said holder to the stringed instrument, substantially as described.

15 2. A stringed instrument of the cithern kind having strings on one side adapted to be tuned in a diatonic scale and strings for fundamentals and their chords on the reverse side, combined with a holder having a seat for a harmonica or mouth-harp, with means for rotatably attaching the same to the stringed instrument, substantially as described.

20 3. A stringed instrument of the cithern kind having strings adapted to be tuned in a diatonic scale on one side and strings for funda-

mentals and their chords on the reverse side, combined with a sound-chamber having a seat for a harmonica or mouth-harp and an opening with a movable cover, and means for attaching said sound-chamber to the stringed instrument, substantially as described.

25 4. A stringed instrument of the cithern kind, combined with an independent sound-chamber, a seat in said chamber for the mouth-harp, and means attaching the sound-chamber to the stringed instrument, substantially as described.

5. In combination, a stringed instrument of the cithern kind, a chart-holder thereon, a mouth-harp stationarily attached to the cithern, a mouthpiece movable on the mouth-harp, and a pointer attached to the mouthpiece, substantially as described.

In testimony whereof I affix my signature in presence of two witnesses.

WILLIAM WATERMAN McCALLIP.
